UNITED STATES PATENT OFFICE.

JESSE R. SMITH, OF BENTON, ILLINOIS.

RAILROAD-TIE RENEWER.

1,381,759.

Specification of Letters Patent. Patented June 14, 1921.

Application filed July 12, 1920. Serial No. 395,660.

To all whom it may concern:

Be it known that I, JESSE R. SMITH, a citizen of the United States, residing at Benton, in the county of Franklin and State 5 of Illinois, have invented new and useful Improvements in Railroad-Tie Renewers, of which the following is a specification.

This invention relates to a railroad tie renewer and aims to generally simplify the construction illustrated in Patent No. 1,081,162, issued to me on December 9, 1913, the weight 10 of the improved construction being materially lessened, thus making it more convenient to handle and to move from place 15 to place.

Another important object of the invention resides in housing the gearing of the apparatus in a portion of the supporting frame, thus protecting the gearing from cinders, 20 rock, gravel or anything else that the road might be plastered with, and which frequently interferes with the operation of a machine of this character.

The nature and advantages of this invention will be better understood when the following detailed description is taken in connection with the accompanying drawing, the invention residing in a construction, combination and arrangement of parts as claimed. 25

30 In the drawings forming part of this application, the like numerals of reference indicate similar parts in the several views, and

Figure 1 is a plan view showing the apparatus in the position for use.

35 Fig. 2 is an end elevation.

Fig. 3 is a sectional view taken on line 3-3 of Fig. 2.

Fig. 4 is a sectional view taken on line 4-4 of Fig. 2.

40 Fig. 5 is a view looking in the direction of the housing member for the gears with the housing plate removed.

Referring to the drawings in detail, A indicates a pair of spaced parallel railroad ties 45 of usual construction, B an intermediate tie adapted to be removed from beneath the rails indicated at C.

The apparatus forming the subject matter 50 of this invention, embodies a frame made up of two spaced side members 10 and 11 respectively, each having the general design or outline illustrated in Fig. 5. The forward corresponding ends of these members are rounded and shaped to provide for what 55 I term nose portions 12, which when the apparatus is in use are adapted to engage

against the web of one of the rails C. The opposite ends of the side members are formed to provide projections 13 which repose upon and are secured to a bar 15, the latter being of a length to rest upon the ties A, being intermediately arched to bridge or span the tie B as shown in Fig. 2. The arched portion of the bar is indicated at 16.

Journalled between the side members 10 and 11 respectively, is a winch 17 to which one end of a cable 18 is suitably secured and adapted to be wound thereon and unwound therefrom. This cable is threaded through an elongated slot 19 formed in a transverse 70 bar 20 arranged between the side members and secured thereto, this bar serving to strengthen and reinforce the frame structure. The free end of the cable has associated therewith a hook like member 21 adapted to engage one end of the tie B as shown in Fig. 1. The axis 23 of the winch projects through the side members of the frame and is secured in position by any suitable means. A ratchet wheel 24 is associated 80 with the axis of the winch and is arranged exteriorly of one of the side members, while pivoted upon this side member is a pawl 25 which co-operates with the ratchet wheel 24 to prevent retrograde movement of the 85 winch as will be readily understood. Rising from the upper edge of each side member of the frame, is a handle 27 by means of which the apparatus in its entirety can be conveniently lifted and carried from place to 90 place.

As shown in Fig. 5, the side member 11 of the frame is recessed as at 28 to provide a housing for the gears 29 and 30 respectively, which are utilized to rotate the winch 95 17 to wind the cable 18 thereabout. The recess 28 and the gears above mentioned are covered by a removable plate 31 which prevents foreign matter, such as cinders, rock, gravel or anything else that the road might 100 be plastered with, from interfering with the operation of the apparatus. The gear 29 is carried by the axis of the winch, while the gear 30, which is smaller than the gear 29, is fixed upon a shaft 32 journaled between the side members of the frame and at the rear of the winch 17. The shaft 32 projects beyond the side member 11 of the frame, and has fixed thereon a ratchet wheel 33, the latter being straddled by the forked 110 extremity 34 of an operating lever 35 which is also mounted upon the shaft 32. A pawl

36 is carried by the lever and coöperates with the ratchet wheel 33 to impart rotation to the shaft 32. Obviously, this rotation is imparted to the winch by the gears 29 and 5 30 respectively.

In practice, the apparatus is arranged upon the railroad in a manner shown in Fig. 1 with the bar 15 reposing upon the ties A and the arched portion 16 thereof bridging 10 the tie B which is adapted to be removed. The cable 18 is extended beneath the rails C, and the hook like member carried by the cable engaged against one end of the tie B. When positioned in the manner stated, the 15 nose portions 12 of the side members of the frame bear against the web of the adjacent rail C so as to hold the frame in position when a pull is exerted upon the cable 18. The operating lever 35 is moved upon its 20 pivot in the proper direction to rotate the shaft 32 and the winch 17, and as the cable 18 winds about the winch, the tie B is removed from beneath the rail. A new tie is placed in position with the same apparatus 25 and with the same operation.

While it is believed that from the foregoing description the nature and advantages of the invention will be readily apparent, I desire to have it understood that such changes 30 may be resorted to when desired as fall within the scope of what is claimed.

What I claim is:

1. A tie renewer comprising spaced parallel side members, a supporting bar secured 35 to the members and projecting from corresponding ends thereof, a winch journaled between the said parallel members, one of said members being recessed, a gear carried by the axis of said winch and arranged with- 40 in said recess, a shaft journaled between the side members at the rear of said winch, a

second gear carried by the said shaft and arranged within said recess and meshing with the gear of said winch, a removable plate associated with said side member and 45 covering the said recess and said gears, means for rotating the said shaft whereby said winch is rotated, a cable having one end secured to the winch and adapted to be wound thereabout and unwound therefrom, 50 a guide mounted on the frame for said cable, a hook like element carried by the free end of the cable, and means for preventing retrograde movement of the winch.

2. A tie remover comprising spaced parallel members, a bar connecting the rear end of said members and projecting beyond the latter, said bar having an intermediate arched portion, the opposite ends of said members being formed to provide nose portions, a winch journaled between said members, one of said members having a recess, a gear carried by the axis of said winch and arranged within the recess, a transverse shaft journaled between said members, a 60 second gear carried by the shaft and arranged within the recess and meshing with the gear of said winch, a plate removably associated with said member and covering the recess and said gears, a ratchet wheel 65 carried by said shaft, an operating lever loosely mounted on the shaft, a pawl carried by the lever and coöperating with the ratchet wheel to rotate the shaft, and said winch, 70 a cable having one end secured to the winch and adapted to be wound about the latter and unwound therefrom, means for guiding said cable, a hook like element carried by the free end of the cable and means for preventing retrograde movement of the winch. 75 80

In testimony whereof I affix my signature.
JESSE R. SMITH.
